UNITED STATES PATENT OFFICE

KARL ALBIN ABRAHAM JOHANSSON, OF STOCKHOLM, SWEDEN

CARD INDEX

Application filed January 8, 1931, Serial No. 507,322, and in Sweden November 17, 1928.

This invention has reference to a card index device for the purpose of holding index cards in a series of containers.

The object of the invention is to provide a card holder in which a series of separate containers or boxes are arranged in a holder that is mounted to rotate on a shaft or axis.

A further object of the invention is to provide in such a device means for removably attaching the boxes to the carrier member; and also to so arrange the boxes that the cards will be practically all located in radial planes; that pass through the axis of the shaft.

Another object of the invention is to provide each of the boxes with a longitudinally extending tube in its base, and a shaft is arranged to engage this tube to mount the boxes.

A further object is to provide a retaining frame between adjacent boxes to maintain them in proper positions.

In the accompanying drawing showing one embodiment of my invention,

Figure 1 is a transverse vertical section as seen on the line 1—1 of Fig. 2.

Fig. 2 is a vertical axial section through the device.

As shown in the drawing the shaft 1 has two discs 2 and 3 secured thereto, the shaft being mounted on suitable arms 4 and 5 extending up from a base 6.

Between these discs are supported boxes denoted generally by 12, composed of a bottom wall 7 and side walls 8 and 9. Suitable curved pins 13 extend across between the side plates, for retaining the cards in the boxes.

In the bottom wall 7 of each box is a series of tubes or sleeves 10 adapted to receive a rod 14. This rod at one end enters a hole 11 in one of the discs 2. A sleeve nut 15 engages the other end of the rod 14, and is threaded into a bushing 17 mounted in the disc 3.

To further support the boxes, a series of channel-shaped frames 16 is extended across between the discs 2 and 3, that will engage

the lower corners of the boxes when inserted.

It will thus be seen that I have produced a comparatively simple device that comprises merely the shaft and two perforated discs, with the boxes that consist merely of sheet metal bent up to a channel form with the sleeves in the bases, and the retaining rods, with the simple bent plates inserted between the boxes, and the rods with the sleeve nuts.

The advantages of a structure of this character are that very thin cards may be used; also the insertion and removal of the cards is very easily effected; and the division into different units is facilitated, and any unit can be removed without disturbing the other units, and easily replaced or another substituted in the carrier.

It is obvious that modifications can be made within the scope of the claims of the invention.

Having now described my invention, what I claim as new and desire to secure by Letters Patent is:

1. A card index device comprising a shaft with a pair of discs thereon, a series of channel-formed boxes, and means for removably mounting the boxes between the discs in a circular series, arranged to receive cards that are substantially parallel with axial planes of the shaft.

2. A card index device comprising a shaft with a pair of discs thereon, a series of channel-formed boxes, and means for removably mounting the boxes between the discs in a circular series, arranged to receive cards that are substantially parallel with axial planes of the shaft, said means comprising a series of longitudinal sleeves in the base of each box, and a rod located in said sleeves with its ends mounted in said discs respectively.

3. A card index device comprising a shaft with a pair of discs thereon, a series of channel-formed boxes, and means for removably mounting the boxes between the discs in a

- circular series, arranged to receive cards that are substantially parallel with axial planes of the shaft, said means comprising a series of longitudinal sleeves in the base of each box, and a rod located in said sleeves with its ends mounted in said discs respectively, one of the discs having an aperture to receive one end of each rod, the other disc having a threaded bushing, and a threaded sleeve mounted in said bushing to engage the other end of the rod.
4. A card index device comprising a shaft with a pair of discs thereon, a series of channel-formed boxes, and means for removably mounting the boxes between the discs in a circular series, arranged to receive cards that are substantially parallel with axial planes of the shaft, and transverse retaining pins at the upper part of each box.
5. A card index device comprising a shaft with a pair of discs thereon, a series of channel-formed boxes, means for removably mounting the boxes between the discs in a circular series, arranged to receive cards that are substantially parallel with axial planes of the shaft, said means comprising a series of longitudinal sleeves in the base of each box, a rod located in said sleeves with its ends mounted in said discs respectively, one of the discs having an aperture to receive one end of each of the rods, the other disc having a threaded bushing, a threaded sleeve mounted in said bushing to engage the other end of the rod, and transverse retaining pins at the upper part of each box.

In witness whereof I have hereunto signed my name.

KARL ALBIN ABRAHAM JOHANSSON.
